UNITED STATES PATENT OFFICE.

JAMES McDONALD BURNETT, OF WESTON-BY-WELLAND, ENGLAND.

ACCUMULATOR GRID OR PLATE.

Application filed May 6, 1924. Serial No. 711,466.

To all whom it may concern:

Be it known that I, JAMES McDONALD BURNETT, a subject of the King of Great Britain, and resident of Weston-by-Wel-
5 land, in the county of Northampton, Eng-
land, have invented a certain new and useful Improvement in or Relating to Accumu-
lator Grids or Plates, of which the follow-
ing is a specification.

10 This invention relates to accumulator grids or plates.

One object of the invention is the provision of a cast unit of lead or lead alloy which can, together with a number of like 15 units, be easily and economically built up to form a complete accumulator plate or grid of any desired dimensions.

Another object is the provision, upon an economic scale, of an accumulator plate or 20 grid of lead or lead alloy which will be strong, rigid and not subject to bending.

Another object is the provision, upon an economic scale, of an accumulator plate of lead or lead alloy which will comprise rigidifying reinforcement but which, at the same 25 time, will have the whole of its exposed surface active.

Other objects and advantages will appear hereinafter.

30 Certain embodiments of the invention are illustrated in the accompanying drawings and the same will now be described, it being understood that the particular constructions and arrangements illustrated and 35 described are susceptible of various modifications without departing from the scope of the appended claim.

In these drawings:-

40 Figures 1 to 3 are perspective and cross sectional views of three examples of units from which accumulator plates are adapted to be built up.

Figure 4 is a side elevation of an accumulator plate built up from units such as that 45 illustrated in Figure 1.

Figure 5 is a cross section of the same taken on the line 5—5 of Figure 4, and

50 Figure 6 is a cross section of an accumulator plate built up from units such as that illustrated in Figure 3.

In Figure 1 a simple unit is illustrated consisting of a cast square lead plate having around its edge a symmetrical groove 1 adapted, as will hereinafter appear, to accommodate a material for binding a num-

ber of such units together edge to edge. The unit is also provided with nine straight sided perforations 2 adapted to accommodate the paste.

The unit illustrated in Figure 2 is similar to that illustrated in Figure 1 except for the fact that the perforations 2 are bevelled as shown so that a greater exposed area of paste can be obtained without the units being unduly weakened.

The unit illustrated in Figure 3 is similar to that illustrated in Figure 1 except for the fact that the edges instead of being grooved symmetrically are recessed as shown to one side, for the purpose, as will 70 hereinafter appear, of enabling accumulator plates of double the thickness of the units to be built up.

In the case of any of these units grooves or corrugations suitable for Planté type accumulators may be substituted for the perforations 2.

Referring now to Figures 4 and 5, the plate here illustrated comprises a number of units such as that illustrated in Figure 1 80 though units in accordance with Figure 2 may be equally well used.

The perforations 2 are packed with accumulator paste 4 and the units are held together in the co-relation illustrated by means of some rigid acid proof conductor such as antimonial lead (which is of greater rigidity than lead) cast into the grooves 1 and also extending beyond the outside units so as to form a strengthening frame 5 around the 90 edge of the plate and a lug 6 by which to attach the plate in position in the accumulator.

In the process of construction of the plate the units are preferably loaded with the accumulator paste while still separate and are then arranged in position edge to edge in a suitable mould. In such position the grooves 1, as will be clear from the drawing, together form a concealed network of 100 inter-communicating intersecting channels extending throughout the whole extent of the plate.

The antimonial lead is then poured or forced into this mould so that it percolates through, and solidified within, the said network of channels, and also forms the frame 5 and lug 6. As will be obvious both the said frame 5 and that part of the antimonial lead which is cast within the intersecting 110

channels constitute a stiffening reinforcement for the plate as well as a connecting means to hold the units thereof together.

Referring to Figure 6 the plate illustrated 5 comprises a number of units such as that illustrated in Figure 3. It is clear from this latter figure that complete symmetrical grooves are formed by placing a pair of the units face to face and as is clearly shown 10 in Figure 6 the complete plate is built up of a number of these units arranged so that such pairs are edge to edge with one another. Otherwise, in respect both of its 15 form and the manner in which it is constructed, the plate illustrated in Figure 3 is similar to that illustrated in Figures 1 and 2.

In both the above described embodiments 20 of accumulator plate it may sometimes be found preferable to apply the accumulator

paste after, and not before the units have been cemented together.

What I claim and desire to secure by Letters Patent is:—

An accumulator plate comprising a plurality of individual unit plates of soft lead, formed each with edge grooves and correlated so that said grooves co-operate to form a hidden network of communicating and intersecting channels running throughout the extent of said accumulator plate, and a concealed framework of rigid conducting material cast within said communicating and intersecting channels and thereby rigidly securing said unit plates together, whereby the whole exposed surface of said accumulator plate is of soft lead but the strength thereof resides in the rigid concealed framework. 25 30 35

In witness whereof I affix my signature.
JAMES McDONALD BURNETT.
